1699

UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S BASQUE.

SPECIFICATION forming part of Design No. 17,751, dated September 27, 1887.

Application filed August 8, 1887. Serial No. 246,465. Term of patent 3½ years.

To all whom it may concern:

Be it known that I, JENNIE SHEILS, of the city, county, and State of New York, have invented and produced a new and original Design for a Pattern of a Lady's Basque; and I do hereby declare that the engraved prints accompanying this specification convey to any one accustomed to using paper patterns a clear understanding of how a garment made up by the pattern will appear.

The design shows close-fitting fronts that display the right front overlapping the left diagonally from the top of the left-shoulder seam to a little below the bust and from this point to the left lower edge, and exhibiting a plaited ornament upon the right front from

the right-shoulder seam to the lower end of the overlap; a close-fitting back that displays two pointed tabs at the center between two points; coat-sleeves displaying full puffs, reaching from the tops half-way to the elbows, and a standing collar.

What I claim as my invention, and desire to secure by Letters Patent, is—

The design for a lady's basque, as shown in the engraved prints accompanying this specification.

JENNIE SHEILS.
